UNITED STATES PATENT OFFICE.

CHRISTIAN C. STOLZENBURG, OF ELYRIA, OHIO.

CUSHION-HEEL.

1,343,528.

Specification of Letters Patent. Patented June 15, 1920.

Application filed August 20, 1918, Serial No. 250,748.

To all whom it may concern:

Be it known that I, CHRISTIAN C. STOLZENBURG, a citizen of the United States, residing at Elyria, in the county of Lorain 5 and State of Ohio, have invented certain new and useful Improvements in Cushion-Heels, of which the following is a specification.

This invention relates to improvements in 10 cushion heels, and it is the principal object of the invention to provide a novel form of anti-slipping tread for rubber or cushion heels, said tread being of a unique design and serving to prevent the slipping of a person 15 son using the same by reason of the firm and positive grip afforded by the coöperating portions thereof.

Another and equally important object of 20 the invention is to provide a heel formed with means for producing air cushions when attached to a shoe and in use, thus, adding to the qualities of the same.

Other objects will be in part obvious and in part pointed out hereinafter.

25 The improvements in the details and arrangement of parts will be apparent from an inspection of the accompanying drawings, in connection with the specific description hereinafter contained and wherein the 30 preferred embodiment of the invention is disclosed for the purpose of imparting a full understanding thereof.

In the drawings:

Figure 1 is a bottom plan view of the 35 improved heel showing the novel form of tread,

Fig. 2 is an edge view thereof,

Fig. 3 is a top plan view of the heel, showing the form of air cushioning means employed,

Fig. 4 is a vertical transverse section through the heel, and

Fig. 5 is an end elevation of the same.

Having more particular reference to the 45 drawings, in connection with which like reference characters will designate corresponding parts throughout the several views, 1 represents the improved cushion heel in its entirety, the same being formed of rubber or some similar material, such as conditions or preference may dictate, having a recess 2 formed in the face or tread portion thereof, preferably, approximately centrally thereof and in form of a bell, the constricted 50 or reduced end of the bell-shaped recess be-

ing disposed toward the rear end of the heel as indicated at 3 and terminating in a small extension forming a vacuum breaking pocket, while the enlarged or flared end of said recess is disposed toward the forward 60 portion of the heel as indicated at 4. In this connection, it may be set out that the forward portions of the sides of the bell-shaped recess are curved as at 5, and as will be readily understood lend to the efficiency 65 of the heel by providing gripping surfaces other than the longitudinally and transversely disposed gripping surfaces and, hence, lessens liability of the slipping of the person using the same, while a strip 2' is 70 arranged across the enlarged portion of the bell and has its tread portion extended beyond the heel tread and the tread portions of the anti-slipping means, hereinafter described, whereby to cause the weight of a 75 wearer to be directed thereonto, thus disturbing the recess 2 and in consequence serving to prevent the retention of dirt and the like therein. Arranged about the bell-shaped recess 2 and formed integral with 80 the tread portion of the heel are a plurality of bell-shaped projections, generally indicated by the numeral 6, these projections being formed with openings 7 located approximately centrally thereof and adapted to receive nails or other fastening devices there-through to permit the securing of the heel to the heel portion of the shoe; washers 8, or similar means, being embedded in the heel and communicating with said openings 90 whereby to insure a positive and strong connection and to prevent the heads of the securing devices from leaving the body of the cushion heel. It may be here noted that the various bell-shaped projections 6 are ar- 95 ranged in disaligned relation and are so disposed as to increase the anti-slipping efficiency of the heel tread so formed; the irregular outline of the projections, obviously, serving to provide a desirable and 100 effective surface engaging means.

Formed on the upper side or face of the heel 1 is a bell-shaped recess or pocket 9 arranged so as to form an air cushion when the heel is attached to the heel portion of a 105 shoe by the fastening devices passed through the openings 7, hence, lending materially to the cushioning or resilient qualities of the heel. To brace that portion of the heel having the recess 9 therein whereby to prevent 110

collapsing of the same under weight, a strip 9' is molded integral with the heel and extends longitudinally through said recess and has an enlargement or head 9^a formed on its 5 free end, which as will be understood, engages with a portion of the heel portion of a shoe.

Attention is directed to the fact that the 10 face of a heel having the air pockets 9 formed therein is dished as at 10, thus, facilitating functioning of the air pockets when arranged adjacent the heel portion of a shoe and also insuring proper engagement 15 of the outer portion of a heel with the heel portion of a shoe to prevent the escape of air from the pockets.

From the foregoing, it will be appreciated 20 by persons skilled in the art that I have provided an exceedingly simple and effectual form of cushion heel and anti-slipping tread therefor; the tread by reason of its design rendering the heel on which it is formed novel, as well as practical.

Manifestly, the construction shown is 25 capable of considerable modification and such modification as is within the scope of my

claim, I consider within the spirit of my invention.

I claim:

A rubber heel comprising upper and lower 30 faces, the lower face having a bell-shaped recess formed therein, a transverse rib across said recess extending beyond the surface of the lower face for engaging the ground to prevent slipping and to prevent accumulation 35 of mud in the recess, the upper face having a bell-shaped recess formed therein, a longitudinal rib in the recess and terminating short of one end and above the central portion of the transverse rib on the 40 lower face for coöoperating with the transverse rib in reinforcing the material between the recesses, an enlargement or head on the terminal end of the longitudinal rib above the central portion of the transverse 45 rib for forcing the central portion of the transverse rib downwardly into the engagement with the ground upon application of weight or pressure upon the heel.

In testimony whereof I affix my signature 50 hereto.

CHRISTIAN C. STOLZENBURG.
